(57) **CLAIM**

The ornamental design for an adaptor for rotary trimmer head, as shown and described.

DESCRIPTION

FIG. 1 is a top, front, and right side perspective view of the adaptor for rotary trimmer head;

FIG. 2 is a bottom, front, and right side perspective view thereof;

FIG. 3 is a front elevation view thereof;

FIG. 4 is a right side elevation view thereof;

FIG. 5 is a top view thereof; and,

FIG. 6 is a bottom view thereof.

The top, rear, and left side elevation view is the same as the top, front and right perspective view in FIG. 1.

The bottom, rear, and left side perspective view is the same as the bottom, front, and right side perspective view in FIG. 2.

The rear elevation view is the same as the front elevation view in FIG. 3.

The left side elevation view is the same as the right side elevation view in FIG. 4.

The portions within the dash-dot lines do not form a part of the claimed invention.

1 Claim, 2 Drawing Sheets
